UNITED STATES PATENT OFFICE.

NORTON T. KESLER, OF ZION CITY, ILLINOIS.

PENCIL-SHARPENER.

No. 884,495.

Specification of Letters Patent. Patented April 14, 1908.

Application filed April 30, 1907. Serial No. 371,163.

To all whom it may concern:

Be it known that I, NORTON T. KESLER, citizen of the United States, residing at Zion City, in the county of Lake and State of Illinois, have invented certain new and useful Improvements in Pencil-Sharpener, of which the following is a specification.

This invention relates to pencil-sharpener, and has for an object, to provide a device of this character with a swinging arm carrying a knife pivoted to a suitable base for angular movement, and adapted to shave a pencil, supported in a suitable manner to the base.

5 In the drawings, Figure 1 is a top plan view of my invention. Fig. 2 is a front view thereof. Fig. 3 is a front view. Fig. 4 is a detail section of the pencil support.

Referring specifically to the drawings, a base and shavings receptacle is indicated at 10, which is supported by padded feet 10'. To provide a large space for the shavings, I form the base of substantially egg shape. A band projects upwardly from the edge of the base 10, and is turned inwardly towards the center thereof, and stops as at 12. Extending upwardly from the base 10 and lying diagonally thereon, is a plate 13, having an inclined edge 14. Adapted to be secured to the plate 13, is a pencil support 15, which comprises an attaching arm 16, and a pencil supporting arm 17 which lies at right angles to the arm 16. The arm 17 is recessed at its upper end as at 19, for the reception of the pencil. To adjust the pencil supporting arm vertically, I provide in the plate 13, a slot 20, through which and into a threaded boss 21 in the arm 16, works a set-screw 22.

A diagonally and upwardly extending screw 23 is provided at one side of the base 10, which works in a boss 24, and has at its upper end, an ear 25. An arm 26 having ears 27, is pivoted as at 28 to the ear 25. The arm 26 is provided at one end with a handle 27, and extending from the arm 26, at the lower end, are projections 28, and from the upper edge projects a lug 29. A knife 30 is placed between the projections 28, and the lug 29, and is held therebetween by a screw 31 threaded through the lug 29 and adapted to bear against the upper edge

of the knife 30. This construction allows the knife to be adjusted lengthwise thereof, whereby the entire cutting edge may be used.

The screw 23 which extends diagonally from the base, and at right angles to the inclined edge 14 of the plate 13, and to which the knife carrying arm is attached, allows adjustment which will regulate the cut of the knife 30. To allow full play of the knife 30, I cut away a portion of the band 11 as shown at 32. By extending a portion of the band 11 inwardly, as shown at 12, it will be seen that free manipulation of the screw 22 is had.

The use of my invention, may be described as follows, the pencil support 15, is adjusted vertically, to give the proper pitch to the pencil supported therein, and the knife supporting arm revolved to lengthen or shorten the screw 23, for regulating the cut. The arm 26 is now given a swinging movement up and down the incline 14 of the plate 13, and the pencil constantly revolved, and the pencil is thus sharpened.

I claim:

1. A pencil-sharpener comprising a receptacle base, a plate secured to said base and having an inclined edge, and a pencil support adjustable on said plate.

2. A pencil-sharpener comprising a receptacle base, a plate secured diagonally on said base and having an inclined edge, a knife mounted on said base for swinging movement on the inclined edge of said plate, and a pencil support comprising substantially right angular arms adjustable on said plate.

3. A pencil-sharpener comprising a receptacle base, a plate secured diagonally on said base and having a slot therein; and a pencil support adjustable in said slot.

4. A pencil sharpener comprising a base, a band extending partly around said base and turned inwardly toward the center thereof, a plate secured to said base and having an inclined edge, said plate having a slot therein, a set-screw disposed within the slot, and a pencil support comprising substantially right angular arms carried by said set-screw and adapted to be clamped to said plate.

5. A pencil sharpener comprising a receptacle base, a plate secured diagonally on said

base and having a slot therein, said plate having a slanting blade-receiving edge, a blade mounted for movement upon said edge, a pencil support, and a screw disposed within 5 in the slot and engaged in the pencil support and arranged for operation to hold the pencil support against movement.

In testimony whereof I affix my signature, in presence of two witnesses.

NORTON T. KESLER.
